DISTRIBUTING MEANS

Edgar R. Troxell, Jr., Bronxville, N. Y., assignor
of one-half to Ralph P. Clarkson, New Ro-
chelle, N. Y.

Application August 18, 1934, Serial No. 740,461

3 Claims. (Cl. 98—39)

My invention relates to distributing means, particularly for conditioned air, and has special reference to the provision of a non-overloading distributing head having a high suction pressure and still maintaining free discharge of air all around the periphery of an open fan.

It is generally recognized that a centrifugal fan of standard design has an extremely low efficiency, of the order of 10%, when maintaining free delivery of air without a discharge housing. It is further recognized that such a fan directly connected to a duct is subject to wide variation in motor speed and in motor load when the static pressure within the duct varies or is different from what the fan is designed to handle. Where high suction pressures are involved, it is particularly important to limit the loading of the fan caused by release of the suction pressure, as otherwise the consequent slowing up of the motor is apt to result in overheating and possible fire.

An object of the present invention is to provide a simple, reliable, and inexpensive distributing head to overcome these objections. A further object is to provide a distributing head that can be used in multiple on a common duct, the head being so devised that even if other heads are not operating and permit leakage of air back through them to the duct, the operating heads will not be overloaded. Another object of this invention is to provide a distributing head so constructed that regardless of error in assuming the section head against which the fan will operate, the distributing head when installed is incapable of overload. A further object is to provide a fan particularly adapted for such a distributing head, capable of developing a high suction pressure efficiency when operating in the open with free discharge of air all around the periphery.

With the foregoing and other objects in view, as will be apparent as the description proceeds, my invention resides in the combination and arrangement of parts and in the details of construction described in this specification and particularly pointed out in the appended claims. I intend no limitations other than those of the claims, it being understood that changes may be made within the scope of what is claimed without departing from the spirit of the invention. In the drawing I have illustrated a preferred form which will accomplish the objects recited and embodies my invention. The drawing, however, is furnished solely for illustrative purposes and I do not desire to be understood as limiting myself to the specific structure therein shown.

In the drawing:

Fig. 1 is a conventional sectional elevation of a distributing head involving my invention and connected to a duct, usually with a number of other heads of identical construction;

Fig. 2 is a plan view of a portion of the discharge ring showing the rubbing knobs;

Fig. 3 is a plan view showing a fragmentary detail of the arrangement of blades in the fan of Fig. 1;

Fig. 4 is a plan view of the secondary chamber or throttling nozzle of Figs. 1 and 5;

Fig. 5 is an enlarged sectional elevational detail illustrative of my invention;

Fig. 6 is an elevational view illustrative of a rubbing knob;

Fig. 7 is a conventional elevation illustrative of a portion of a duct with a plurality of distributing heads connected thereto;

Fig. 8 is a perspective sketch of the throttling nozzle of Figs 1 and 6;

Fig. 9 is a fragmentary perspective sketch of the assembly, omitting the rubbing knobs.

Similar reference characters refer to corresponding parts throughout the views.

Fig. 1 illustrates a diffusing and distributing head of the same general type as shown in co-pending application Serial Number 711,643 filed Feb. 17, 1934, which application was abandoned Sept. 23, 1935 and is particularly designed to draw air from a duct 3 and discharge same into a space mixed with induced air from the space in the desired proportion drawn through openings 18.

The head comprises a suction housing 2, preferably a light weight casting, attached to the duct 3 and preferably supporting a motor 10 as by straps 8, 8, fastened to the bosses 12, 12, and adjusting screws 9, 9, through support arms 11, 11. Preferably a felt collar (not shown) is placed around motor 10 to deaden vibration and to close whatever gap may exist between the motor and the encircling portion of the housing 2. Attached to shaft 19 of motor 10 by a hub 7 is a fan disk 6 having a plurality of blades 5, 5, spaced at or near the outer edge of the disk.

A discharge ring 14 may be provided, adjustably supported by posts 15, 15, whereby the gap below fan disk 6 may be varied at will to provide varying amounts of induced air drawn through openings 18 in the closure plate 17 which is removably attached to the cover member 16, the latter, in turn, being fastened to plate 14. In this construction all moving parts are concealed from below but access to fan and motor is permitted.

Radially disposed on plate 14 I prefer to provide a plurality of rubbing knobs 13, 13, to create

turbulence in the discharged air stream, thus diffusing the discharged air into the space. These knobs, in rubbing the air stream also tend to shower the discharge downwardly and outwardly. 5 the dash line A designating the normal position of ceiling or wall surface. Knobs 13 are generally of semi-bulbous shape with the larger end towards the outside and, being symmetrical, the direction of rotation of the fan may be either 10 way. Being set radially, the rubbing knobs 13 lie across the discharge direction of the air, as indicated by the arrows (Fig. 2) and divert and diffuse it into the air of the space.

The particular fan which I prefer for this type 15 of distributing head, in order to secure high suction pressure, has approximately the specific relationships shown in Fig. 3. A disk 6 has at or near its periphery a plurality of blades 5, 5, comparatively narrow and close together. For a 12" 20 diameter fan, 1750 R. P. M., delivering 450 cfm. against a suction pressure of 0.5" W. G. the preferred proportions of the various parts are approximately as shown in Figs. 3 and 5.

Essential features of such a fan are the angle 25 at which the blades are set, and the backward angle or pitch of the blades with their concave faces forward as the fan rotates. In this instance the rotation is counter-clockwise, as indicated by the arrow (Fig. 3). I prefer that the blades 30 be formed in the arc of a circle of which a radius drawn from the center of the blade makes an angle of forty-five degrees with that radius of the blade circle which passes through the inside leading edge of the blade. Similarly, the 35 chord of the arc formed by the concave forward face of the blade is at 45 degrees to the same radius of the blade circle.

Preferably, though not necessarily, a top ring 4 is provided to support the upper ends of the 40 blades 5, 5. It will be observed that this fan is sealed on one face by the disk 6 and no air can enter the fan except from the throttling intake. Hence, only duct air is handled by the fan and the creation of a restricted suction intake by well 45 known calculations for the flow of air through an orifice is not nullified by leakage or flow of air to the blades from elsewhere.

Preferably suction housing 2 is formed by concentric tubular members spaced apart as by partitions 1, 1, the space between forming an air passage as indicated (Figs. 1 and 5) in the form of a throttling nozzle which may extend within the fan and deliver air to the inside of the blades, the entrance opening being of predetermined proportions based on the desired air delivery and suction pressure to be developed. This forms, in substance, a secondary chamber between the duct and the fan with a restricted entrance so that if, for example, a number of such heads are 50 attached to the same duct and one or more stop operating, thus temporarily permitting air to leak back through these non-operating heads to the duct, the operating heads will not be overloaded. Similarly, if the coils for heating or cooling are 55 removed from the duct circuit, the heads may still be operated for ventilation without overloading the motors by abnormal reduction in the speed of the fan because of loading. Nor will a

leak in a ventilating duct circuit cause overloading of the distributing heads.

The reason for this prevention of overloading is that the construction described permits the air within duct 3 to reach the fan only by passage 5 through the annular orifice and passageway created between the two concentric tubular members forming the suction housing. This throttling orifice is of a specific predetermined area for any given fan and thus limits the quantity of air which 10 can flow from the duct to the fan when any given suction pressure is created by the fan within the suction housing.

Partitions 1, 1, also provide means to diminish the rotation or "fanning" of the air drawn within 15 the secondary chamber and aid in guiding the flow of air, without turbulence, to the blades.

It is apparent that the construction indicated in Fig. 5 may be used, if desired, without discharge ring 14, cover member 16, and closure 20 plate 17, the fan running directly in the open air and having absolutely free discharge of air all around its periphery. The preferred construction, however, is that shown in Fig. 1 where substantially free discharge of air all around the periphery of the fan is obtained, the slight friction of air on plate 14 and the diffusion caused by knobs 13 rubbing the discharged air being of little effect in the loading of the fan.

What I claim is:

1. In combination, a supply duct provided with a plurality of openings, a distributing head adjacent to each opening, each said head comprising an open centrifugal type suction fan having substantially free discharge of air all around its 35 periphery, air intake means communicating with said duct on one face only of said fan, the other face of said fan being sealed whereby only duct air can pass through said fan when said fan is operating, a motor operatively connected 40 to drive said fan, means included in the structure of each head providing an admixture of air from the space served with the discharge of duct air from said fan, and means so constructed and arranged that change in the discharge of one of said distributing heads by reason of the stoppage of another of said heads and the leakage of space air back through said stopped head, is obviated.

2. In combination, an open centrifugal type 50 suction fan having substantially free discharge of air all around its periphery, a housing for said fan on the suction face directing the flow of sucked in air to the interior edges of the blades of said fan, means to seal the other face of said fan from 55 the intake of air, whereby only sucked in air passes through said fan blades when said fan is operating, a motor operatively connected to said fan and supported within said housing, and means providing an admixture of air from the 60 spaced served with the discharge of sucked in air from said fan.

3. A structure as defined in claim 2 in which said last named means includes a discharge ring below said fan said ring being supported by said 65 housing and provided with an opening for the passage of space air upwardly therethrough.
